BUBBLING CANDLE LAMP

Frank Pettit, Union, N.J., assignor to Noma Lites, Inc.,
New York, N.Y., a corporation of Delaware

Filed June 26, 1961, Ser. No. 65,714

Term of patent 14 years

(Cl. D48—20)

FIG. 1 is a top plan view of a bubbling candle lamp showing my new design;

FIG. 2 is a side elevational view thereof; and

FIG. 3 is a bottom plan view thereof.

The dominant features of the design reside in the portions shown in full lines.

I claim:

The ornamental design for a bubbling candle lamp, substantially as shown and described.
